(57) **CLAIM**

The ornamental design for an arm for paper trimmer, as shown and described.

DESCRIPTION

FIG. 1 is a perspective view of the arm for paper trimmer;
FIG. 2 is a front view;
FIG. 3 is a top view;
FIG. 4 is a left end view;
FIG. 5 is a rear view;
FIG. 6 is a bottom view; and,
FIG. 7 is a right end view thereof.

The broken lines in the figures showing portions of the paper trimmer in FIGS. 1–7 are for illustrative purposes only and form no part of the claimed design.
